UNITED STATES PATENT OFFICE

SEIFERT W. ROUSSEAU, OF BALDWIN, NEW YORK

DOOR OPERATING MECHANISM

Application filed March 7, 1929. Serial No. 345,024.

This invention relates to door operating mechanisms and pertains particularly to mechanisms designed to permit simultaneous operation of a plurality of doors.

It is an object of the invention to provide a mechanism which shall be extremely simple in its construction and operation, but which will operate positively and easily at all times.

Other objects and advantages of the invention will appear hereinafter.

A preferred embodiment of the invention selected for purposes of illustration is shown in the accompanying drawings, in which,

Figure 1 is a top plan view of the mechanism as applied to a pair of garage doors, the roof of the garage being removed to better disclose the construction and operation of the mechanism;

Figure 2 is a section on the line 2—2 of Figure 1;

Figure 3 is an enlarged detail sectional view of the traveller member;

Figure 4 is a section on the line 4—4 of Figure 3, and

Figure 5 illustrates the method of attaching the arms to the traveller member when connected to open both doors to the same extent.

Referring to the drawings, the apparatus comprises a guide member 1, preferably of a shallow channel form which may be secured to the tie beams 2 or ceiling of the building in any suitable manner. Mounted for reciprocation along the guide 1 is a traveller member 3 which preferably comprises a U-shaped member 4 embracing the guide member 1 and having a pair of shafts 5 extending transversely thereacross, the said shafts being preferably rigidly secured to the member 4 by means of nuts 6 which engage threaded ends of the shafts. Mounted for rotation on the shafts 5 are corresponding rollers 7 which track on the bottom of the channel portion of the guide 1.

The doors 8 which are to be operated receive their angular movement about their hinges from the reciprocating member 3, rigid links 9 and 10,—which may be of channel iron,—preferably forming the connection

between the member 3 and the doors. The connection of the links with the doors may be secured by pivot pins 11 and with the member 3 by a king pin 12. If both doors are to be opened to the same angular extent the links 9 and 10 may both be connected to the king pin 12 as illustrated in Figure 5. Lock nuts 14 retain the links upon the king pin.

But it may be desirable to open one of the doors to a greater angular extent than the other. This will be the case, for example, when the line of access to the doors is not at right angles to the plane of the doors when closed—i. e. to the plane of the opening—but is inclined to one side or the other. In this case the operating mechanism is assembled in the manner illustrated in Figures 1, 3 and 4. Here it is seen that the link 10 has been shifted and one end—which may be designated the inner end—pivoted to the other link 9 while the other or outer end has been moved nearer the hinged edge of the door.

To provide for this selective assembling or adjustability of parts, each link near its inner end is formed with a series of holes 16 and the other link is pivotally secured at a selected hole by a bolt 17 and lock nuts 18. As illustrated in Figure 1, the link 10 is secured at its end to link 9, but it will be apparent that the end of link 9 may be similarly secured to link 10 when it is necessary to open the other door wider.

At the outer ends of the links where they are attached to the doors, the adjustable connection is secured through pivot bars 15. These bars may be of angle form with their vertical flanges secured to the door and their horizontal flange formed with a series of holes 13 for pivot bolts 11.

Means is provided for holding the doors in either open or closed position. Referring to Figures 3 and 4, mounted on the U-shaped member 4 is a transverse shaft 18 pivotally supporting a latch member 19 having a downwardly extending prong 20 and an upwardly extending arm 21. The latch 19 is unbalanced on the shaft 18 so that the prong 20 normally rests on the bottom of the channel-shaped guide member 1, and the guide member is provided (see also Figure 1) with suit-

ably positioned apertures 23 into which the prong 20 may drop in order to hold the doors in any desired position of adjustment. Preferably one of the apertures 23 is located near 5 the outer end of the guide 1 in proper position to hold the doors open, while the other aperture 23 is located near the inner end of the guide member in proper position to hold the doors closed.

10 In order to release the latch 19 so that the doors may be opened or closed as the case may be, a suitable pull-cord 24 may be secured to the arm 21, and the free end of the said pull-cord led to any desired position for 15 convenient operation, preferably to one of the doors.

In installing the apparatus, the guide member is first secured in the desired position with the traveller member 3 mounted thereon 20 and the links 9 and 10 are then connected to the doors and the traveller member in suitable arrangement to provide the desired amplitude of movement in operation. As will be observed, by properly positioning the 25 pivot bars 15 and by securing the links 9 and 10 thereto in proper aperture, corresponding to the point of connection to the other link or to the travelling member as the case may be, the doors may be caused to open more or less 30 widely as desired. When it is desired that the doors shall both open to the same degree, the arms 9 and 10 are connected to the traveller member 3 through the bolt 12, but when it is desired that one of the doors shall open 35 more widely than the other, one of the arms is connected to the other arm in such position as to give the desired variation, and the other arm alone is connected to the bolt 12.

In operation, assuming that the doors are 40 open as illustrated in Figure 1, the pull-cord 24 is drawn forward to cause the latch 19 to be disengaged from the aperture 23, after which one or the other of the doors is moved in closing direction. As will be observed, 45 movement of one of the doors is sufficient to cause simultaneous movement of the other door in unison therewith, and if the doors have been properly installed, closure of the two doors will be effected simultaneously. 50 When the doors are fully closed, the latch 19 engages the inner aperture 23, thus locking the doors in closed position.

When it is desired to open the doors, the pull-cord 24 is again drawn forward to disengage the latch, after which opening movement of either one of the doors causes the other door to open simultaneously.

It will be apparent that the mechanism may have various other embodiments within the 60 spirit of the invention as set forth in the subjoined claims.

What I claim is:

1. Door operating mechanism comprising in combination, two mating doors hinged at 65 their opposite outer edges, and means for co-

ordinately opening each of said doors selectively by various degrees but closing the doors always to the same position, said means including a travelling member movable at right angles to the plane passing through the hinge axes of said doors, links connected at their outer ends with said doors and operatively connected with said travelling member at their inner ends, transverse strips having a series of elements providing adjustable pivotal attachment for the outer ends of said links to the doors, a king pin forming the connection for one of said links, or when desired for both of said links, with said travelling member, said links at their inner ends being provided with a plurality of adjustment holes, and a pivot pin for securing one link upon the other in adjusted positions when the other is secured by said king pin.

2. Door operating mechanism comprising in combination, two mating hinged doors, and means for coordinately opening each of said doors selectively by various degrees but closing the doors always to the same position, said means including a travelling member movable at right angles to the plane defined by the pivot axes of said doors, links connected at their outer ends with said doors and operatively connected at their inner ends with said travelling member, means for adjusting the connection of the outer ends of said links transversely of said doors and means for adjusting the connections for the inner ends of said links.

In testimony whereof, I have signed my 100 name to this specification this 5th day of March, 1929.

SEIFERT W. ROUSSEAU.
